UNITED STATES PATENT OFFICE.

OTIS M. KENNEDY, OF PHILADELPHIA, PENNSYLVANIA, ASSIGNOR TO THE CUNNINGHAM PIANO COMPANY, A CORPORATION OF PENNSYLVANIA.

PLAYER-PIANO.

1,379,926.

Specification of Letters Patent.

Patented May 31, 1921.

Application filed October 8, 1917. Serial No. 195,296.

To all whom it may concern:

Be it known that I, OTIS M. KENNEDY, a citizen of the United States, residing at Philadelphia, in the county of Philadelphia and State of Pennsylvania, have invented 5 certain new and useful Improvements in Player-Pianos, of which the following is a specification.

This invention relates generally to player 10 pianos and specifically to a novel construction and arrangement of expression controlling devices, whereby pneumatic player pianos may be operated by an inexperienced performer to obtain with great accuracy the 15 correct expression of the music in accordance with the usual expression indications on the music roll, and hence to reproduce the musical composition with substantially the correct expression intended to be given to the piece 20 by the original composer. Furthermore, the expression controlling mechanism hereinafter described has the additional advantage that it does not require any special character 25 of music roll but is adapted to be used with all standard music rolls which have thereon any of the usual expression lines or symbols, and this mechanism and its adjuncts may be applied to any player piano without interfering 30 with the control of the expression devices by means of the usual manually operated control buttons, if it be so desired.

An important novel feature of my invention is a pressure regulating device adapted 35 to control the pneumatic pressure effective 40 to operate the usual pneumatics of a player piano regardless and independent of the amount of pressure or degree of vacuum created by an operator of the piano in pumping the treadles, as usual for obtaining the necessary vacuum for operating player 45 pianos. Another important novel feature is the means hereinafter described whereby the expression controlling mechanism may be thrown into or out of operation at the will 50 of the operator and which in operation controls the action of the pneumatics no matter how great a suction is applied by the operator tending to result in too strong an action of the pneumatics and thereby interfering 55 with the correct expression which should be given the piece being played, especially as respects the soft and very soft tones which are often necessary to get the desired and technically accurate expression. Furthermore, the pressure regulating mechanism may

be used either independently of, or in conjunction with, certain known mechanical devices which tend to control the expression, such as means for adjusting the position of the treble and bass hammer rails and the loud 60 pedal or string damper controlling devices.

I have, therefore, provided in a player piano, manually controllable mechanism for actuating both a pressure regulating expression device and a mechanism for controlling 65 the expression, each of which may be used either simultaneously or selectively as may be desired, to thereby enable any persons, especially inexperienced ones operating a player piano, to more correctly reproduce to 70 a very fine degree of accuracy, the proper expression intended to be given to the music by the composer as indicated by the line or symbols on the music roll.

Finally my invention comprises an im- 75 proved construction and arrangement of the various operating parts in a pneumatically operated expression controlling device for player pianos, as will appear from the description of the mechanism hereinafter more 80 particularly set forth and pointed out in the appended claims.

In the drawings forming a part of this application there is illustrated one form of mechanism for carrying out my invention, 85 but it is to be understood that the particular form illustrated is not necessarily essential to the invention, except as hereinafter specifically stated, and many alterations and modifications may be readily made without 90 departing from the scope of the invention.

In the drawings annexed hereto, Figure 1 is a front elevational view showing certain parts in section, while Fig. 2 is a perspective view showing a manually operated controlling lever with the connections to the indicator diagram and controlling valve. Fig. 3 is an enlarged view of one form of controlling valve together with the pressure regulating mechanism, partly in elevation 100 and partly in section. Fig. 4 is a bottom plan view of the valve casing shown in Fig. 3, while Fig. 5 is a top plan view of the valve. Fig. 6 is a side elevation of the pneumatic portion of the pressure regulating 105 mechanism shown in Fig. 3, while Fig. 7 is a sectional view of the same. Figs. 8 and 9 show a modification of the form of valve illustrated in Figs. 4 and 5, while Figs. 10 and 11 represent a front elevation and side 110

elevation respectively of a still further modified form of controlling valve.

Referring to Fig. 1 of the drawings, at 1 is shown the upper casing of the piano and at 2 the usual keyboard, while the hammers and usual movable hammer rails 3' are illustrated diagrammatically in their relative positions to coact with the piano wires 4 shown in the upper part of Fig. 1 of the drawings in the manner well-known in the art. Any suitable form of operating mechanism, such as the treadles 5 may be used to actuate the feeders 6 and create the necessary pneumatic pressure used in operating the usual pneumatic devices of the piano, as by exhausting the air from the primary valve chamber 7, which may be of any usual construction known in the art. A suitable communicating conduit 8 may be used to connect the upper and lower action mechanisms and extends between the chambers 7 and the exhaust feeders 6, as is shown in Fig. 1. A suitable form of pneumatic motor 9 is also conveniently shown for operating the music roll 10 through suitable gearing, and the motor 9 may be operated from the feeders 6, as is also well-known in the art, while any form of automatic tracker device 11 may be used to properly position the roll over the tracker board 12, and, moreover, in the form of music roll illustrated herewith is shown an expression line 13 common on most standard music rolls, or its equivalent descriptive words, letters or other symbols 13', equally common (see Fig. 2), to facilitate the operator's control of the expression devices hereinafter set forth. In Fig. 1 is also shown a common form of tempo scale 14 and pointer 15 therefor, together with the usual operating levers 15' whereby the pointer may be properly adjusted in accordance with a recognized form of tempo indicating means 14' on the music roll, the elements so far described being well-known to those skilled in the art.

As indicated above, this invention includes certain novel combination and arrangements in expression controlling mechanisms and as a part of this construction there is shown in Fig. 1 of the drawings a plurality of pneumatic devices T, B and L adapted to control the position of the hammer rails for the treble and bass notes on the piano and the loud pedal or damper releasing mechanism, respectively. These devices may be suitably operated from the feeders 6 in a manner that is well understood in the art, and by reason of the link connections to the hammer rails and dampers the pneumatic devices illustrated diagrammatically at B and L, and at T in section, see Fig. 1 constitute means for mechanically controlling the expression by properly positioning the hammer rails or string dampers.

Moreover, pneumatic bellows for me-

chanically controlling the expression may be suitably placed under the manual control of the operator through an expression controlling valve mechanism 16 operated by a movable finger shown in the drawings at 20. 70 This finger member 20 may be pivoted at any suitable point on the piano, as adjacent the keystrip 2' and may be connected by a suitable mechanism, such as a rod 17 and an arm 17', fixed to a vertical rod 18, to which is secured an upper arm 19' to which is pivoted a link 19 adapted to be pivoted to the movable member 21 positioned adjacent the music roll 10 as shown in Figs. 1 and 2 of the drawings. 80

Various forms of mechanism could be utilized for controlling the operation of the valve 16, and the form I have illustrated in the drawings is merely shown by way of example and comprises an adjustable connecting rod 24 connected to the finger piece 20 at one end and at the other end to a bracket 25 secured to the sliding valve member 26. This valve 26 is located in a suitable valve casing 27 and any form of retaining means may be used to slidably secure the valve 26 in position. From the valve casing a series of tubes T', B' and L' extend to the treble, bass and loud pneumatic devices T, B and L, respectively. The valve 26 is intended to control the admission of air to each of these tubes and thereby control the operation of their respective pneumatics. For this purpose the valve 26 may be provided with an opening 28 adapted to place the tube T' in communication with the atmosphere through the passage 29 in the valve casing 27, and since it may be desired to provide a mechanism whereby the bass and treble pneumatics may be operated successively or simultaneously *in seriatim* as desired, the tube B' is connected to passages 30 and 31 through the valve casing as shown. The valve 26 is provided with an opening 32 adapted to open passages 30 100 and 31 and thus place the tube B' in communication with the atmosphere, while a certain opening 33 in the sliding valve member when appropriately moved establishes communication by way of a longitudinal 110 endwise connection 34 with the atmosphere and places the tube L' in communication therewith. Suitable channels 35 and 36 are also provided in the face of the valve 26 so that both the tubes B' and T' may be 120 placed in communication with the atmosphere at once.

Coacting with the means described for controlling the expression of the music produced by the player piano to a relatively 125 nice degree of perfection, I preferably provide a mechanism for controlling the pneumatic pressure used for operating the usual pneumatics of the piano, thus providing a second operated means to control expression 130

by regulating the pressure under which the entire action of the piano takes place, which mechanism, if desired, could, of course, be used independently of the mechanical expression device above described, and the operation of both forms of expression-varying means may be readily placed under the manual control of the operator. This additional pressure regulating means 5 for controlling the expression, which has been provided, is indicated generally at 40 in Fig. 1 of the drawings and comprises a pneumatically operated pressure regulating valve adapted to be placed in operative connection with the main exhaust tube 8 extending between the primary valve chamber 7, which actuates the pneumatics in the piano, and the lower pneumatic action mechanism included in the feeders 6 operated from the treadles 5 described above. Means are provided whereby this pressure regulating valve may be thrown into or out of operation at will by the operator in accordance with the correct expression intended to be given to the music as may be indicated on the music roll and, moreover, the sliding valve 26 above described for controlling the operation of one form of expression device, forms a convenient means 25 for also controlling the action of the valve mechanism 40, although separate operating means could readily be devised, and for this purpose a tube C is connected at one end to the valve casing 27 as indicated in the drawings and at the other end to the casing of the control valve mechanism 40. The valve 26 is provided with an opening 41 to coöperate with a passage 42 adapted to place the tube C in communication with the atmosphere, as will hereinafter appear, so as to be effective to throw the control valve mechanism 40 into or out of operative connection with the main conduit 8 which controls the pneumatic condition of the primary valve chamber 7.

In the pressure regulating mechanism 40, as shown, the outer casing 50 is provided with a plurality of internal chambers 52 and 53. The chamber 52 is adapted to be connected directly to one portion 54 of the main conduit 8 while the other chamber 53 is in communication with the end 55 of the other section of the tube 8, and in normal operation the air is exhausted through the end 54 of the tube 8, upper chamber 52, lower chamber 53 and end 55 of the adjacent section and thence to the feeders 6, this constituting the main pressure conduit for the piano. A valve 60 is interposed between the chambers 52 and 53 and its position is controlled by the tube C from the manually operated valve 26 above described. Means for controlling the position of the valve 60, as shown in the drawings as one form of a suitable construction, is by way of the pneu-

matically operated primary valve 62 provided with a seating member 62' adjacent to which is a flexible diaphragm or pouch 61 separating the chamber 53 from a lower chamber 63 with which the tube C communicates. A relatively small opening 64 connects the chamber 53 to the tube C through the small chamber 63 for the purpose that will hereinafter appear. This primary valve 62 forms one means for controlling the admission of air to a tube 65 to control the valve 60. The tube 65 leads to a chamber 66 covered by a thin flexible pouch or diaphragm 67 similar to pouch 61, adjacent to which is located a member 68 connected by a stem 69 to move in unison with the valve 60 so that if air is admitted beneath the pouch 67 the vacuum in the chamber 53 will immediately cause the pouch 67 to engage the member 68 and raise the valve stem 69 and the valve 60 to its seat against the upper portion of the chamber 53. The upper chamber 52 is connected by means of a pipe 72 to an opening 73 in the chamber of a pneumatic 74 and an opening 75 therein is connected by way of a second tube or pipe 77 to the chamber 53 described above so that when the valve 60 is closed against its seat, the air must pass from the chamber 52 of the tube 8, through opening 73 to the chamber 74 and thence from the chamber 74 through an opening 75 and pipe 77 to the chamber 53 and thence to the end 55 of the main tube 8, this circuitous conduit forming a shunted passage for the air from the main tube 8. In this shunted passage may be located the pressure regulating valve 80 so that as the passage of air is passed through the chambers 52 and 53 or shunted through the lower chamber 74 this regulating valve may be thrown into and out of operation. This valve 80 is adapted to be automatically operated to control the passage of air through the pneumatic to the pipe 77 when the control mechanism is thrown into operation by the closure of the valve 60, as indicated above. Various forms of valve controlling devices might be readily used as means to regulate this opening. In the form shown in the drawings, which is merely illustrative of one means for carrying out this feature of the invention, a pivoted valve 80 is located on a movable wall of the pneumatic chamber 74 so as to move therewith and a leaf spring 81 is adapted to normally tend to force the valve 80 into closing position while a stop 82 engages the fixed projection 83 on the casing of the pneumatic in order to prevent the spring 81 from effecting a closing of the valve opening 75 when the pneumatic is in non-closing or open position. The pneumatic 74 is adapted to be collapsed by the pneumatic suction on the tube 77 through the tube 8

and suitable means for opposing this action and tending to open the valve is by way of a spring 90 suitably interposed between a fixed part of the pneumatic 74 or 5 other suitable fixed part of the piano casting, the other end of the spring 90 being attached to a link 92 fixed to the movable wall of the pneumatic 74. It will thus be seen that as the suction holds the pneumatic 10 closed, it does so against the action of the spring 90 and the spring 90 immediately tends to open the valve 80 by tending to hold the pneumatic 74 in open position. Any suitable means for adjusting the tension of the spring 90 may be provided to regulate this automatic action of the pressure regulating valve 80, and, as shown, consists in a pin 91 extending through the coils of the spring and as the spring is turned 15 the coils will cause the spring to move relative to the pin 91. The other end of the spring 90 may be swiveled to the connecting link 92 in order to facilitate this adjustment.

20 25 In order to provide a pressure regulating mechanism which will be very sensitive in operation and respond quickly in the desired control of the pneumatic pressure as above indicated, I have provided within the collapsible chamber 74 an auxiliary pneumatic device 100 connected by a passage 101 to the valve opening 75 in the suction tube 77. It will thus be seen that the valve 80 controls the passage of air from both the main collapsible pneumatic 74 and the auxiliary 30 35 compensating pneumatic 100 so that the valve 80 more evenly controls the pressure throughout the entire chamber 74 rather than simply around the valve 80 which 40 45 would otherwise tend to be the case and hence the entire operation of the pneumatic 74 is very sensitively responsive to the action of the suction on the tube 77 and against the spring 90 which tends to open the pneumatic chamber 74 as above indicated.

50 As stated above, the pneumatic device for adjusting the position of the hammer rail for the treble notes is shown in section in Fig. 1 to illustrate a conventional form of pneumatic device for operating the hammer rails as well as the loud pedal. Although well known in the art, one of these pneumatics will be described to show clearly their connection with the rest of the automatic 55 expression mechanism. Thus the bellows 105 is connected by a link mechanism 106 extending upwardly at the rear inside corner of the casing of the piano to the treble hammer rail 3'. The upright member 106 60 is suitably connected to the hammer rail 3' so as to adjust the position of the rail and limit the rebound position of the hammers when the link member 106 moves downwardly. The pneumatic 105 is connected by 65 a passage 107 to a chamber 108 in which is

located an opening 109 to the atmosphere adapted to be controlled by a double valve 110. Valve 110 has a head 111 located within the vacuum chamber 112, this chamber being connected by a pipe 113 to the main 70 suction mechanism for the piano. The air inlet tube T' connects with a passage 114 in the casing of the pneumatic and extends into a separate chamber above the valve head 111. Between this chamber and the head is located a diaphragm adapted, when operated, to engage the head 111 and operate valve 110. Normally the air passes from the atmosphere through the opening 109, passage 107 to the bellows 105, keeping the same inflated and in open position. However, when air is admitted through the tube T' either from the hand operated buttons or the controlling valvular mechanism above described, the same enters the passage 114 and forces the diaphragm into engagement with the head 111 on the valve 110 closing the opening 109 and at the same time opening up the passage 107 to the vacuum chamber 112. It will thus be seen that the action of 90 the main suction device for the piano will then immediately cause an exhaustion of the air in the bellows 105, causing it to collapse and consequently effecting an operation of the link mechanism 106 to move the hammer 95 positioning rails 3', thereby shortening the throw of the hammers in striking the piano wires. This construction described is merely one form of mechanism for operating pneumatically the position of the treble and bass 100 hammer rails as well as the loud pedal and other forms of pneumatics may readily be used. Moreover, these pneumatics may be controlled manually by the usual control buttons, or from the valve 26 in the manner 105 fully described above, and, as stated, the valve also forms means for controlling the action of the pressure regulating mechanism 40, although it is to be understood that this pressure regulating mechanism may also be 110 controlled independently of the valve for controlling the pneumatics T, B and L.

The operation of the entire mechanism which has been provided as indicated above for controlling and obtaining very accurate 115 expression to music being rendered by a player piano, will now be described.

The operator, while pumping the treadles 5 to exhaust the feeders 6 and effect an operation of the player piano in the usual manner, may, by use of the finger piece 20, and link mechanism 17, 18, and 19, adjustably move the pointer member 21 to rest over the proper positions from time to time on the indicating diagram 22, as is denoted 120 by the expression line 13 or other equivalent letters or symbols on the music roll. If this line or any form of expression indicia indicates that a loud expression should be given to the music, the finger piece 20 is 125 130

moved to the right in Fig. 1, causing the member 21 to move in the same direction until the same is located over the indication F or FF. By reason of the link connection 5 24 operated by the finger piece 20, in unison with the indicator member 21, it will be seen that the valve 26 is also moved a corresponding distance, but in the opposite direction, or toward the left in Figs. 1 and 3, so 10 that the opening 33 comes into communication with the passage 34 in the valve casing and places the same into communication with the atmosphere, permitting air to pass into the tube L' to the loud pneumatic L, 15 effecting an actuation of the same to release the piano wire dampers in a manner that will be well understood in view of the operation above described of the pneumatic T since the pneumatic L may be arranged to 20 operate in the same manner. This operation of the mechanism automatically gives a loud and resounding expression to the music as will be readily understood.

When the line on the music roll indicates 25 that a soft expression should be given to the music, the operator moves the finger piece 20 to the left moving the indicator 21 over to the left of the diagram 22, and at the same time the valve 26 will be moved in 30 the opposite direction or toward the right in Figs. 1 and 3. A movement of the valve 26 to the right will cut off the passage of air to the loud pneumatic through the tube L' and first bring the opening 28 into alignment with the passage 29 which is connected to the treble pneumatic tube T'. The admission of air to this pneumatic will cause the same to operate in the manner above described, moving the treble hammer rail near 35 the strings to soften the action of the hammers in striking the treble notes. If now, the lever or finger piece 20 be moved still farther to the left, the valve 26 will be moved farther to the right, causing the opening 28 40 to be cut off from communication with the tube T' through the passage 29, and causing the opening 32 to register with the passage 30 to the tube B' admitting air to the bass pneumatic B. It will thus be seen that 45 either the loud, treble or bass pneumatics 50 may each be actuated independently of the others. By moving the finger piece 20 still farther toward the soft and very soft positions, the channel 35 will eventually place 55 the passage 29 again into communication with the atmosphere to permit air to enter the treble pneumatic tube T', and, by reason of the location of the channel or trough 36 which at the same time maintains the passage 60 30 to the bass pneumatic tube B' in communication with the atmosphere, it will be seen that in this position of the valve both the bass and treble pneumatics are in simultaneous operation to effect a softening 65 of both the treble and bass notes of the

piano by a mechanical, in contradistinction to a pneumatic means.

If now, the finger piece be moved still farther toward a position to give a very soft expression, as may be called for by 70 the expression line 13 on the music roll, the valve 26 will be moved still farther to the right as shown in Figs. 3, 4 and 5 and bring the opening 41 into communication with the passage 42 to the tube C which controls 75 the action of the pressure regulating device 40 to bring into action the pneumatic means which has been provided for controlling the expression. When air is thus admitted to the tube C, the same enters the chamber 80 63 in the casing 50 beneath the thin diaphragm 61, causing this diaphragm to engage the head 62' on the valve stem of the valve 62 raising the same from its seat and admitting air to the tube 65 and chamber 85 66 below another thin flexible pouch 67 causing a similar actuation of the same to close the valve 60 against the seat. Since this valve 60 is interposed in the main suction tube 8, it will effect a shunt of the air 90 passage from this tube and compel the action of the feeders 6 in exhausting the air from the chambers 7 to cause the air to pass by way of the pipe 72 from the upper chamber 52 to the chamber of the pneumatic 74, 95 thence from the pneumatic through the opening 75 controlled by the valve 80 to the pipe 77 and chamber 53, thence to the main suction tube 8.

It will thus be seen that when the valve 100 60 is closed the pneumatic pressure, which is effective to operate the main pneumatic devices of the piano, will be under the control of and regulated by the valve 80 which automatically operates in the following 105 manner: The suction from the feeders 6 through tube 8 and pipe 77 tends to normally collapse the pneumatic 74. The valve 80, being attached to the upper movable wall of the pneumatic, is therefore actuated 110 by the action of the pneumatic in collapsing to move to closing position over the end of the pipe 77, thus restricting and limiting the suction exerted on the pipe 8 and if there is a strong action in the feeders 6 due 115 to strenuous pumping, for example, tending to quite completely exhaust the air from the upper part of tube 8 and valve chamber 7 thereby causing a strong action of the pneumatic devices in operating the hammers of the piano, the control valve 80 moderates the action of the usual pneumatics and renders the same correspondingly less powerful to such a degree as to obtain 120 a delicate and soft expression corresponding to the human touch rather than a mechanical, resounding and loud expression, no matter how great a pressure is operated on the feeders 6.

It will be noted that the valve 80 is pre- 130

vented from being actually closed or at least from being maintained in closed position by reason of the spring 90 which is interposed between the collapsible wall of the pneumatic 74 and the fixed wall thereof, or any fixed position in the piano, to immediately tend to open the pneumatic and hence the valve 80 whenever the same is drawn to closing position by the suction 10 on the tube 8. The tension of the spring 90 may be readily adjusted as indicated above so as to give the same a relatively small amount of energy, so that its action is more readily overcome by the action of 15 the suction from the feeders 6 and in this manner further means are provided whereby the pneumatic action in the piano, by reason of this pressure regulating mechanism, may be brought down to such a fine 20 degree as to make the same extremely soft and delicate regardless of the strength of the pumping action on the feeders 6 by an operator using the pedals 5 or by any other source of power which might be used as, 25 for example, an electric motor. By moving the valve 26 so as to cut off communication from tube C to the atmosphere, the valve 62 closes by reason of the lowering of diaphragm 61 due to the suction from 30 chamber 53 through the small opening 64 and tube C on the chamber 63. The parts then assume the normal position with the valve 60 open.

It will be noted that the valve 80 is pivoted to the movable wall of the pneumatic 35 74 and a spring 81 normally tends to force the valve 80 toward closing position. This is for the purpose of insuring a tight closing of the valve 80 regardless of the position 40 at which the wall of the pneumatic may assume in closing relatively to its rear or fixed wall, since this flexibility between valve 80 and pneumatic 74 permits of a further downward movement of the bellows 74 after the valve 80 is seated thus 45 requiring a less degree of refinement in properly adjusting the position of the parts. In order to prevent the spring 81 from actually closing the valve 80 when the pneumatic 74 is open and the valve 80 should 50 likewise be open the valve 80 is provided with a stop or projection 82 adapted to engage a stop 83 on the front wall of the pneumatic 74 to prevent the valve 80 from closing, as will be apparent from an inspection 55 of Fig. 7.

As indicated above, in the description of the apparatus, the auxiliary pneumatic device 100 located within the flexible chamber 60 74 and provided with a passage 101 opening into the chamber 74 adjacent the opening 75 to the pipe 77, is for the purpose of providing a more accurately operating pressure regulating device by reason of the fact 65 that the valve 80 controls both the auxiliary

pneumatic 100 and the main pneumatic 74. It will thus be seen that the valve 80 on the one hand will more evenly control the pressure in the entire pneumatic chamber 74 and and these two chambers, on the other hand, will be more quickly acted by the feeders 6 tending to control the position of valve 80, thus making a very sensitively operating device for regulating the pressure of the air used in operating the piano. 70

In the modified form of valve construction shown in Figs. 8 and 9, I have arranged the various passageways so that the pressure regulating mechanism 40 may be thrown into operation before the hammer rail controlling pneumatics are operated, and have also provided a construction whereby the pneumatic pressure regulating mechanism 40 may be used independently of, as well as simultaneously with, the treble 85 and bass pneumatics for operating the position of the treble and bass hammer rails. An inspection of these figures will readily disclose that the passage 41'', corresponding to the passage 41 in Fig. 5, will come 90 into alignment with the passage 42' to the tube C in Fig. 8 before either of the other passages 28 or 32 open up the tubes T or B to the atmosphere and hence the pressure regulating mechanism 40 may be independently operated by shifting the position of the valve 26 with the passages 41'' and 42' in alignment. Moreover, it will be apparent that if the valve is moved farther to the extreme right, the channel 110 will 100 continue to admit air to the passage 42' and tube C, when both the tubes T' and B' are at the same time open to the atmosphere, and in this manner both the hammer rail controlling pneumatics and the pressure regulating mechanism will be in simultaneous operation. In Figs. 8 and 9 it will also be noted that the passage 35 extends entirely up to, and communicates with the opening 28 in the sliding valve, and, moreover, the tubes T' and B' are changed around so that the tube B' communicates with the passage 30 shown in Fig. 8 and the tube T' communicates with the passage 29. In this manner, when the operating lever is moved 110 to obtain a softening effect, as just stated, the pressure regulating mechanism 40 is first thrown into action by reason of the passage 41'' and the channel 110 opening the passage 42' and upon a further movement of the lever toward the soft tone obtaining position the opening 28 and passage 35 open up the passage 29, which in this case is connected to the bass pneumatic tube B', thus softening the bass notes first 125 before a further movement of the valve 26 toward the right causes the opening 32 to communicate with the passage 30 which actuates the treble pneumatic to soften the treble notes. In view of the channels 35 130

and 110 it will be noted that the pressure regulating mechanism is continued in operation and the bass pneumatic controlling the hammer rail for the bass notes is also maintained in a position to soften the tone of these notes. When the valve is operated in the opposite direction, it will be noted that the treble note controlling pneumatic is first thrown out of operation by reason of the 10 opening 32 cutting off communication with the passage 30, the passage 35 in the meantime still controlling the soft action from the bass notes but a further movement toward the loud position of the operating 15 lever causes the passage 35 and opening 28 to cut off communication with the passage 29, which in this case controls the loud pneumatic through the tube B'. A further movement of the valve 26 to the left in 20 Fig. 8 will then cut off communication between the passage 42' and either the channel 110 or the opening 41" in the valve 26, thus cutting off the action of the pressure regulating mechanism 40 bringing the valve 25 into neutral position.

In Figs. 10 and 11 I have shown a further modification as to the construction of the controlling valve 26, which in this case is shown as a rotary valve instead of 30 the sliding valves shown in the other modifications. In this construction the operation of the mechanism is substantially the same as that described above in connection with Figs. 1 to 7. The pivoted finger piece 20 in Fig. 10 is connected at its lower end by a link or rod 24 to a rotary circular disk 115 which is provided with suitable openings to control the admission of air to the several tubes T', L', B' and C in substantially the same manner in which the control 35 of the air to these tubes is effected in the other forms of valve. For this purpose the several tubes lead to a fixed circular plate 116 provided with any suitable means, as a 40 flange 117', by which the same may be secured to the piano casing. The disk 115 is shown as being provided with an opening 117 adapted to register over the tube L' when the valve is located in the loud expression obtaining position. The disk 115 is also provided with another transverse 45 passage or opening 119 and on the inner surface of the disk 115 extending in the arc of a circle whose center is the center of the disk 115 is a coacting groove 120 terminating in the transverse passage 119 at one end. The opening 119 may also be in communication 50 with a radially extending passage 121 to the peripheral edge of the disk 115 for a purpose of increasing the effective operation 55 of the valve in opening the passage to the tube B', the two passages 119 and 121 also coacting to prevent an accumulation of dirt in either, due to the circulation of air 60 around through both, when in operation.

The disk 115 is further provided with an opening 123 and a slot 124 connected thereto located on the inner face of the disk, adapted to coact with the passage to the tube C to place this tube in communication 70 with the atmosphere at the proper time in the operation of the valve. This opening 123 may also be provided with a more or less radially extending passage 125 similar to the passage 121. Any suitable means for 75 rotatably securing the valve disk 115 in position on the supporting plate 116 may be provided, and one means comprises a bolt 126 extending through both plates and provided with a washer 127 adjacent the front 80 disk 115 with a spring 128 interposed between the washer 127 and a second washer 129 on the bolt, on which is also located the nut 130, which may be tightened up as desired to cause the spring to resiliently hold 85 the disk 115 flat against the face of the rear plate 116 and at the same time permitting the disk 115 to be readily rotated by the rod 24 connected to the finger piece 20.

The various openings in the disk 115 are 90 so positioned that the actuation of the finger piece 20 will cause the various tubes L', B', T' and C to come into communication with the atmosphere in order to give the correct expression to the music in substantially the 95 same manner as that obtained by use of the sliding valve illustrated in Figs. 1 to 7. For example, when the finger piece 20 is moved to the right, the opening 117 will register with the passage to the tube L' and 100 operate the loud pedal pneumatic and when in this passage it will be noted that each of the other tubes is cut off from communication with the atmosphere. However, when the finger piece 20 is moved to the left to 105 obtain a softer tone, the loud pneumatic tube L' is cut off, and the opening 119 first registers with the passage to the tube B' causing an actuation of the bass pneumatic device to adjust the position of the bass hammer 110 rail in the manner described above. Further movement of the finger piece 20 to the left, or in the direction of the arrow shown in Fig. 10, also moves the disk 115 in the direction of the arrow shown on the same, so 115 that the curved slot 120 will soon place the tube T', as well as the tube B' in communication with the outside air to cause a simultaneous actuation of both the pneumatics controlled by the tubes T' and B'. This is 120 substantially the position of the valve 115 as shown in Fig. 10, where it will be noted that both the tubes B' and T' are in communication with the passageways 121 and 119 by reason of the curved slot 120. It 125 will be noted that the opening 125 has not yet reached the passage to the tube C, which controls the action of the pressure regulating pneumatic device 40, as in the other modifications. Thus a further movement of 130

the finger piece 20 in the direction of the arrow will place the tube C in communication with the atmosphere by reason of the passage 123. In this position both the tubes 5 T and B are still in communication with the air by reason of the position of the passages from these tubes and the slot 120, and both the mechanism for controlling the hammer rails and the mechanism for regulating 10 the pneumatic pressure in the piano are then operating simultaneously to give a very delicate and soft tone to the music.

In this modification it will be noted that when moving the valve to obtain a soft expression, the bass notes are first softened by 15 action of the bass pneumatic, the treble notes are next softened by the passage 120 opening communication to the tube T' to actuate the treble pneumatic, and then the 20 pressure regulating device further softens the treble and bass notes by reason of the action through the tube C. Upon a reversal of the movement of the lever 20 to obtain a louder tone, it will be seen that the pressure 25 regulating mechanism is first thrown out of action, then the treble note pneumatic is cut off from communication with the air to increase the tone of the treble notes and upon 30 a further motion of the lever 20 in the direction opposite to that shown by the arrow in Fig. 10, the bass pneumatic through the tube B' is cut off from communication and the bass notes are then operated with a louder tone and the valve assumes a neutral 35 position before further movement in the direction just mentioned will again throw into operation the loud pneumatic by reason of the opening 117 registering with the loud pneumatic tube L'.

40 In connection with either of the forms of controlling valves shown herewith, it will be noted that, as indicated, the finger piece 20 may be positioned over a central portion of the indicator diagram 22 designated as 45 "medium" and in this position, neither the mechanism for mechanically controlling the position of the loud pedal or bass and treble hammer rails, nor the pressure regulating 50 expression controlling device, are in operation. In this position of the finger piece, the piano may be operated in the ordinary way with the expression controlling devices in neutral or inoperative position, and the 55 expression may then be controlled by the usual hand buttons as is well known in the art. From this description of the various modifications of operating valves and positions of the tubes L', T', B' and C it will be 60 apparent that the control of the various expression devices constituting the subject matter of my invention may be effected in various manners, as indicated, so that either the bass notes may be softened before the 65 treble notes are softened or the action may

be reversed and the treble notes may be softened before the bass notes are so acted upon, and, moreover, the pressure regulating mechanism may be thrown into action either before or after the treble and bass 70 pneumatics are operated to mechanically control the expression in the manner hereinbefore indicated by adjusting the position of the hammer rails.

Having thus described my invention I 75 claim and desire to protect by Letters Patent of the United States—

1. A player piano comprising, in combination, pneumatics, including connecting devices, operating to vary the position of the hammer rest rail and thereby actuating the treble, bass and loud pedal instrumentalities, respectively, player pneumatics, pneumatically-actuated valvular means operatively interposed in the main suction conduit leading to the player pneumatics and operative to maintain a uniform operative tension therein regardless of a higher tension created in the main source of pneumatic tension, and manually actuated valvular means having ports and passages adapted to be successively brought into communication with each of said sets of pneumatics, and operable to selectively control the operation of said pneumatically-actuated regulating valve as also, independently, control the tension in each of said first mentioned pneumatics for operatively adjusting the effective position of each of said expression instrumentalities, at the will of the operator. 90

2. In a player piano, the combination with player pneumatics for operating the string hammers in accordance with perforations in a music roll, a divided hammer rest rail, other pneumatics operable to vary the position of each section of said hammer rail to vary the expression, a source of pneumatic tension including a main suction conduit leading therefrom and operatively connected to said player pneumatics, and means to independently vary the expression, comprising a divided valve chamber having a communicating opening, interposed in said conduit, pneumatically-actuated valvular means governing said valved opening and thereby controlling the pneumatic tension delivered from said source of tension to said player pneumatics to operate the string hammers, and a manually actuated valvular device having a plurality of ports and passages adapted to be selectively brought into communication with the atmosphere and operable for throwing into and out of operation said pneumatically actuated valvular means governing the tension operating the player pneumatics and also operable, at the will of the operator, to actuate the pneumatics to vary the effective position of said sectional hammer rail. 110

3. In a player piano, the combination of 130

- player pneumatics, adapted to operate the string hammers in accordance with perforations in a music roll, a main source of pneumatic tension, a main suction conduit 5 leading therefrom and operatively connected to said pneumatics, and a pneumatically-actuated regulating valve interposed in said suction conduit and operable to control the pneumatic tension deliverable to said player pneumatics, a sectional hammer rail and string dampers, a plurality of pneumatics operable to vary the position of said last mentioned instrumentalities required for the treble and bass notes and loud pedal effects, 10 15 respectively, and a manually operable valvular device having a series of ports and passages adapted, at the will of the operator, to be brought into selective communication with said regulating valve controlling the tension operating the player pneumatics and with each of said pneumatics operable to adjust the effective position of said expression instrumentalities.
4. In a player piano the combination with 20 a divided hammer rest rail and string dampers, pneumatics, operable for adjusting the effective position of said instrumentalities required for the treble, bass and loud pedal notes, player pneumatics for operating the 25 string hammers by and in accordance with melody perforations in a movable music roll, a main source of pneumatic tension, a main suction conduit leading therefrom and operatively connected to said player pneumatics, a divided valve chamber having a 30 valved opening, interposed in said main suction conduit, pneumatically-actuated valvular means governing said valved opening; and a manually-operable valvular device 35 having ports and passages adapted to selectively govern said first mentioned pneumatics, and an additional port and passage adapted to be brought, at the will of the operator, into position to also actuate said 40 pneumatically operated valvular device in the main suction conduit and thereby independently vary the expression given to the melody notes by varying the pneumatic tension delivered to and operating said player 45 pneumatics.
5. In a player piano, the combination with 50 player pneumatics for operating the string hammers of the piano in accordance with perforations in a music roll, a main source of pneumatic tension including a suction conduit leading therefrom and operatively connected to each of said pneumatics, a divided valve chamber interposed in said conduit and having a connecting passage 55 way between its chambers, pneumatically-actuated valvular means controlling said passage way and operative to control the pneumatic tension delivered through the same from said source of tension to said 60 player pneumatics, and a manually actuated 65
- valvular device for establishing communication with the atmosphere and thereby throwing into and out of operation said pneumatically-actuated valvular controlling means.
6. In a player piano, the combination with 70 player pneumatics, for operating the string hammers in accordance with perforations in a music roll, a main source of pneumatic tension including a suction conduit leading therefrom and operatively connected to each 75 of said pneumatics, a divided valve chamber interposed in said conduit and having a communicating passage way between its chambers, a valve governing said passage way, a pneumatically-operated device actuating said last mentioned valve, said combined means being operable to maintain substantially constant the pneumatic tension passing deliverable to and actually effective 80 for operating said player pneumatics regardless of any excess of tension produced in said source of tension, and pneumatic means to move said pneumatically actuated valve into and out of normal position, comprising a manually operable valvular device 85 for establishing communication with the atmosphere and with said last mentioned pneumatic valve-actuating means.
7. In a player piano, the combination of 90 player pneumatics, including connecting devices, adapted to operate the string hammers in accordance with the melody perforations in a music roll; a main source of pneumatic tension, including a main suction conduit leading therefrom and operatively connected 95 to each of said pneumatics, a pneumatically-actuated valvular device interposed in said suction conduit, and manually operable valvular means adapted to establish communication with the atmosphere, at the will 100 of the operator, to effect the operation of said pneumatically operable valvular device to control the pneumatic tension deliverable to said player pneumatics and the expression of the melody notes produced by the 105 player pneumatics notwithstanding any excess of pneumatic tension produced in said main source of pneumatic tension.
8. In a player piano, in combination, 110 player pneumatics, a main source of pneumatic tension and a main suction conduit leading therefrom and operatively connected to said pneumatics, a divided valve chamber interposed in said conduit, a pneumatically operated valve and a normally 115 open passage way governed thereby between said chambers, tubular means connecting said chambers above and below said valved opening and constituting a shunt passage, a pressure regulating valve governing said 120 tubular shunt passage and normally closing the same, pneumatic means governing the actuation of said regulating valve to open communication of the lower of said 125 valve chambers with the atmosphere, and 130

means to throw into and out of operation said last mentioned pneumatic means, said combined mechanisms being operable to control and maintain substantially uniform and constant the pneumatic tension actually effective for the operation of all of said player pneumatics.

9. In a player piano, the combination of player pneumatics, a divided valve chamber 10 interposed in the main suction tube of the instrument which extends between the main source of pneumatic tension and said pneumatics, a pneumatically operated valve and a connecting passage way governed thereby between said chambers, a by-passage 15 connecting said chambers above and below said valved passage, regulating valvular means controlling the admission of atmospheric air through said by-passage, and 20 pneumatic means to effect the actuation of said regulating valvular means, and operable to control and maintain substantially uniform and constant the pneumatic pressure delivered to and actually effective for 25 the operation of each of said player pneumatics.

10. A player piano having in combination pneumatically operated playing devices, a source of pneumatic tension from which is 30 derived the pneumatic tension for operating said devices, and a main suction conduit between said elements, a divided valve chamber interposed in said conduit, a pneumatically operated valve, an opening governed thereby between said chambers, a shunt passage 35 connecting said valve chambers above and below the valved opening therein, and a pneumatically operated regulating valve, including adjustable means for causing 40 yielding resistance to its action, operable to open and close communication of said passage with the atmosphere and thereby reduce an excess of pneumatic tension passing through said valved opening and maintain 45 a uniformity of pneumatic tension in said player pneumatics.

11. In a player piano, in combination, player pneumatics, a main source of pneumatic tension and a main suction conduit 50 between the same and said pneumatics, and means to control the tension delivered through said conduit, said means comprising a divided valve chamber interposed in said conduit, an opening between them, a valve 55 governing the opening between said chambers, a shunt passage connecting said chambers above and below said valved opening therein, a regulating valve in said shunt pas-

sage, normally closing the same and operable to open communication with the atmosphere, pneumatic means tending to close said regulating valve and resilient means tending to yieldingly open said valve against the action of said pneumatic means, and manually operable valvular means to actuate said 65 pressure regulating valve mechanism.

12. In a player piano, in combination, mechanism for controlling the pneumatic tension required to effectively operate the player pneumatics, comprising a divided 70 valve chamber interposed in the main suction tube of the instrument, a pneumatically operated valve, and a normally open communication between said valve chambers, a shunt conduit connecting said chambers, and a tension regulating mechanism adapted to 75 actuate said valve to close the opening between said chambers and open communication between the lower chamber thereof and the atmosphere, and thereby control the 80 pneumatic tension passing through said divided valve chamber, said mechanism comprising a pneumatic in operative communication with said shunt passage and with the atmosphere, a valve pivotally mounted on a 85 movable wall of said pneumatic and independently movable with respect thereto, and means to effect an independent movement of said last mentioned valve.

13. In a player piano, in combination, 90 mechanism for controlling the pneumatic tension required to effectively operate the player pneumatics, comprising a divided valve chamber interposed in the main suction tube of the instrument, a pneumatically 95 operated valve, and a normally open, communication between said valve chambers, a shunt conduit connecting said chambers, and a regulating mechanism adapted to control the pneumatic tension passing to the player 100 pneumatics through said divided valve chamber, said mechanism comprising a pneumatically actuated valve governing said shunt passage, said valve being mounted on the inner side of a movable wall of its operating pneumatic, and independently movable with respect thereto, and an auxiliary compensating pneumatic supported within 110 said last mentioned pneumatic and also connected with the suction tube under said valve, whereby said valve is operable by both said main and auxiliary pneumatics.

In witness whereof, I have hereunto set my hand this 5th day of October, 1917.

OTIS M. KENNEDY.
